UNITED STATES PATENT OFFICE.

WARD LEATHERS, OF HAWORTH, NEW JERSEY.

TURBINE-DRIVEN CAR AND LOCOMOTIVE.

Application filed September 2, 1920. Serial No. 407,798.

To all whom it may concern:

Be it known that I, WARD LEATHERS, a citizen of the United States, residing at Haworth, in the county of Bergen and State of New Jersey, have invented new and useful Improvements in Turbine-Driven Cars and Locomotives, of which the following is a specification.

The object of my invention is to provide a suitable application of a high-speed light-weight prime-mover to the truck of a car or locomotive especially where designed for use on rails. My invention is applicable also to road vehicles.

The present day locomotive with the exception of some electric locomotives is provided with side connecting rods between drivers, which, owing to their intermittent application of power and their pounding operation are mechanically insufficient and destructive. One of the objects of my invention is to eliminate these side connecting bars.

Another object is to provide such speed reduction that the drivers may be of small enough diameter to follow the rails safely without the guide truck as now used where locomotive drivers are of large diameter, experience having shown that large driving wheels tend to climb the rails when not guided. A further object is to get all the weight of boiler engine and supplies of fuel and water on the driving wheels so as to have no parasite load on wheels exerting no tractive effort.

A further and important object of my invention is to produce a light, inexpensive, and compact self-driven truck for use under passenger and freight cars the motive fluid for which may be furnished by a steam boiler or generator located on each car, or on only some of the cars, or on a special car the purpose of which would be to carry the generator, its auxiliaries, the fuel and water, and quarters for the fireman. The engineer may drive from either end of the "generator car" or he may drive from either end of any car, a practice now common with all motor-driven electric trains. Naturally at least one "generator car" would be required in each

train but its location in the train could be immaterial. With unusually long trains such as tremendously long freight trains more than one "generator car" might be used, preferably distributed through the train. Although the steam generators described in my numerous patent applications could be sufficiently automatic to require little attention beyond providing fuel to the bunkers, such as fuel oil or pulverized coal, and water, it would be preferable in some cases to have the steam generator of sufficient size to furnish motive fluid to an entire train located on a special car where a trained fireman could observe its operation. Such a special "generator car" would preferably be self-driven to the same extent as the other cars in the train. Such special "generator car" may in some cases have a portion of its enclosed space used for baggage or mail or passengers. Such "generator car" would be used for the production of motive fluid which it would furnish at an automatically maintained pressure to a train line in which there would be a throttle or throttles under the control, manual, pneumatic, electric or otherwise of the engineer. This is an especially practical system since in steam railroad practice the exhaust is not condensed. Preferably there would be a throttle for each car or truck or prime-mover and the throttle would be opened or closed proportionately to all the other throttles on the train by well-known pneumatic or electric control. On shorter trains such as used for suburban passenger service a single steam throttle could be provided at each end of every car, any one of which could be manually operated by the engineer for turning steam into every prime-mover used for propulsion on the train. Such prime-movers could be, if preferred, small, high-speed, high-pressure reciprocators properly connected to serve the purpose of the turbines illustrated.

In the following specification, I describe my invention and to make the text more clear, I have appended drawings in which similar numbers characterize similar things.

Figure 1 is a diagrammatic plan view of a six-wheel truck.

Fig. 2 is a diagrammatic side view of Fig. 1.

Fig. 3 is a diagrammatic side view of a two-wheel truck.

5 Fig. 4 is a diagrammatic plan view of another form of truck with six wheels.

Fig. 5 is a diagrammatic side view of Fig. 4.

Fig. 6 is a modification of Fig. 5.

10 Fig. 7 is a diagrammatic side view of a turbine drive unit for a self propelled car.

Fig. 8 is a diagrammatic end view of Fig. 7.

15 Fig. 9 is a diagram of a turbine drive with speed reduction first through a spur reduction gearing and second through a worm reduction gearing.

Fig. 10 is a view of Fig. 9 taken at a right angle.

20 Fig. 11 is a diagram of another form of a turbine drive with speed reduction first through a worm reduction gearing and second through a spur reduction gearing.

Fig. 12 is a view of Fig. 11 taken at a right angle.

In Figs. 1 and 2, 1 is any prime-mover. It may be an electric motor or a gas or gas-steam turbine, but, preferably, a steam turbine of suitable type for automotive use.

30 It may be a plain disc viscosity turbine, or a corrugated disc turbine as illustrated in my patent application Serial Number 395,-222.

35 2 is a worm and worm-gear which gives the speed of the turbine rotor its first reduction. The turbines 1, 1 may or may not be on the same shaft. If desired a separate turbine may drive each pair of drive wheels shown at 3, 4, 5 or one turbine may drive 40 all the drivers on the truck, or even on both trucks if desired.

45 Power from the turbines 1, 1 is transmitted to the drive wheel axle through the worm reduction gear 2, the flexible connection 6, the telescopic connection 7, the flexible connection 8, and the worm reduction gear 9, the gear of which is integral with the axle, which is rigidly joined to the wheels.

50 The turbines as shown in Fig. 1 may obviously be placed in the center of the car or locomotive as well as at the side, in which case the worm-reduction-gearing may be placed off center. The gear 2 may 55 also be omitted and replaced by a turbine placed with its shaft vertical in which case turbines 1 are changed from the position shown with horizontal shafts to a position with vertical shafts, the turbine shafts being substituted for the vertical shafts of the worm gears in worm gearing 2, 2.

60 The telescopic connection 7 may be a longitudinally splined joint, and the splines or longitudinal serrations may be provided 65 with balls or rollers if desired. This per-

mits of the up and down movement of the wheels and axles, or of the truck frame.

The worm-gearing 9 is housed in a housing 10, integral with which is a torsion member 11, on the top of which is a guide 12. 70 This guide may be of any suitable construction which permits of vertical movement and no fore and aft movement. It may be round or flat, but if flat, as shown, it may also be permitted a slight sidewise movement which is distinctly useful owing to a slight sideplay of the wheels. The guide 12 is held in guide members not shown rigidly connected to the spring supported frame of the truck. Such frame is common to all 75 car trucks. This frame also carries the turbines 1 and the worm-gears 2.

In Fig. 3, 13 represents the truck frame which carries the turbine or turbines and the worm-gears 2, one for each axle. The torsion members are here shown at 14 supported from axle to axle. This is a very desirable arrangement on four-wheel trucks for car use but I prefer the arrangement shown in Fig. 2 for heavy locomotive use. 80 The torsion members 14 need only maintain a straight line between the axles; movement in all directions which does not change the straight line may be permitted. Flexible joints such as shown at 15 may be used 85 between the turbines and the worm-reduction gears if desired.

In Figs. 4 and 5 I have shown the power transmitted from the turbines 1 to the wheel axles through two worm-reductions as in 100 Figs. 1, 2 and 3, but with the shaft of worm wheel 2 used horizontally. The power is transmitted through a worm-reduction 2, a universal or flexible joint 16, a telescoping joint 17, a worm-shaft 18 and a worm-gear 19 to the axle. Power is further transmitted from the worm-shaft 18 to the next 105 axle through the universal or flexible joint 21, the telescoping joint 22, the connecting shaft 23, the universal or flexible joint 24, the worm-shaft 18 and the worm-gear 20. In a six-wheel truck the power may be further transmitted to the next axle in similar manner.

Housing 25 surrounding the worm-gear 2, 110 together with the turbine, or turbines, 1, is carried on the spring-supported truck frame. Housings 26 for the worm-gears 19 are supported on the axles but provided with torsion members 27 for the purpose of 115 preventing the housings from rotating with the axles. These members 27 are integral with or integrally connected to, the housings 26 on one end and are hinged or swivelled at the other end as shown at 28.

120 Fig. 6 is the same as Fig. 5 except that the worm-gear 2 is changed to a gear-reduction consisting of suitably constructed gears 29, preferably of herring-bone construction. A turbine or turbines, drives one 125

of the gears 29, through a flexible connection if desired. The other gear drives the drive wheels in manner similar to the worm-gear in Fig. 5.

In Figs. 7 and 8, 1 is a turbine the power of which is transmitted through the flexible connections 30 and 31, the shaft 32, the worm-gear reduction 2, the shaft 33, and the worm-gear reduction 34, to the axle 20. The 10 turbine is shown mounted on yieldable means of support. Such means may be pneumatic, hydraulic, magnetic, or mechanical such as springs. 35 is a reversing lever which turns the motive fluid from one jet to the other as illustrated in my patent application on corrugated disc turbines referred to. The reverse lever is operated by the engineer by suitable means, local or remote, mechanical, electrical, pneumatic or otherwise. Motive fluid is admitted at 36, exhaust is at 37. The valve 38, when closed, will shunt preferably part of the exhaust gases into the pipe 39 which communicates with the heating system on the car or the 20 train. Where the yielding means of support is not used the flexible connections 30 and 31 may be eliminated and the outboard bearing 40 may be dispensed with if desired. The torsion member 11 and the 25 guide 12 serve the same purpose by the same means as 11 and 12 in Fig. 2.

In Figs. 9, 10, 11 and 12 I have illustrated some of the other obvious means of reducing the speed of the turbine as the power is transmitted from it to the axle. In Figs. 9 and 10 the turbine drives through a spur-and-gear-reduction and a worm-reduction. In Figs. 11 and 12 the turbine drives through a worm-reduction and a spur-and-gear-reduction. It is also possible to use two spur-and-gear-reductions, or to use but one reduction, worm or gear, or to add a worm or a gear reduction to any of the foregoing or illustrated gear trains. In Fig. 11 I have two turbines or two separated turbine "stages" which may be used if desired. It is evident that where the prime-mover is carried on the axle such as illustrated in Figs. 7 to 12 practically the entire assembly except the torsion member may be turned about the axle any number of degrees desired and there located for its normal running position.

Having fully set forth my invention in form understandable to those familiar with these arts, I wish it distinctly understood that there are innumerable obvious and easily provided variations in arrangement, in application, and in details of construction all of which fall within the scope of my invention.

I claim:

1. In a turbine driven vehicle a rigid member, a turbine, a driving axle, a gearing system, a vertical, flexible and extensible

connecting member, a gearing housing and a torsion member, said rigid member being located above and spaced away from said driving axle and adapted to support said turbine and the first gearing of said gearing system, said gearing housing being located on said driving axle and adapted to enclose and support the final gearing of said gearing system, said vertical, flexible and extensible connecting member being adapted to connect the gearings of said gearing system, said torsion member being attached to said gearing housing and provided with a guide on its outer extremity, said turbine being adapted to drive said driving axle through said gearing system and said vertical, flexible and extensible connecting member. 70

2. In a turbine driven vehicle a rigid member, a turbine, a driving axle, a speed reduction gearing system, a vertical, flexible and extensible connecting member, a speed reduction gearing housing and a torsion member, said rigid member being located above and spaced away from said driving axle and adapted to support said turbine and the first speed reduction gearing of said speed reduction gearing system, said speed reduction gearing housing being located on said driving axle and adapted to enclose and support the final speed reduction gearing of said speed reduction gearing system, said vertical, flexible and extensible connecting member being adapted to connect the speed reduction gearings of said speed reduction gearing system, said torsion member being rigidly attached to said speed reduction gearing housing and provided with a guide on its outer extremity, said turbine being adapted to drive said driving axle through said speed reduction gearing system and said vertical, flexible and extensible connecting member. 85

3. In a turbine driven vehicle a rigid member, a turbine, a longitudinally extending shaft, a plurality of driving axles, a speed reduction gearing system comprising a plurality of right angle speed reduction gearings, a plurality of vertical, flexible and extensible connecting members, a plurality of speed reduction gearing housings, and a plurality of torsion members, said rigid member being located above and spaced away from said driving axles and adapted to support said turbine, said longitudinally extending shaft and a plurality of right angle speed reduction gearings, each of said speed reduction housings being located on respective said driving axles and adapted to enclose and support the respective final right angle speed reduction gearings of said speed reduction gearing system, said vertical, flexible and extensible connecting members being adapted to connect the speed reduction gearings on respective driving 100 105 110 115 120 125 130

axles with respective speed reduction gearings on said rigid member, each of said torsion members being attached to respective said speed reduction gearing housings and provided with a guide on its outer extremity, said turbine being adapted to drive said driving axles through said longitudinally extending shaft, speed reduction gearing system and connecting members.

WARD LEATHERS.
